UNITED STATES PATENT OFFICE.

CHARLES E. BERG, OF MCINTOSH, MINNESOTA.

MAIL-BOX SIGNAL.

Application filed August 8, 1923. Serial No. 656,396.

To all whom it may concern:

Be it known that I, CHARLES E. BERG, a citizen of the United States, residing at McIntosh, in the county of Polk and State of Minnesota, have invented certain new and useful Improvements in Mail-Box Signals; and I do hereby declare the following to be a full, clear, and exact description of the invention, such as will enable others skilled in the art to which it appertains to make and use the same.

This invention relates to a mail box signal and particularly to such signals which are used on rural mail boxes. As is well known, mail deliveries are now extensively made in rural districts. The mail boxes are, according to post office regulations, required to be situated along the highway traveled by the mail carrier. The dwellings of the parties served are often a considerable distance from the highway and it is desirable to have signals on the boxes for the observance of both the party served and the mail carrier. The mail carrier collects outgoing mail and it is objectionable to have him stop to look for such mail if there is none in the box.

It is an object of this invention, therefore, to provide a signal structure comprising two signals, one of which is adapted to indicate mail delivered and the other of which is adapted to indicate outgoing mail.

It is a further object of the invention to provide two such signals, one of which can be quickly operated by the mail carrier to indicate delivered mail and the other one of which is adapted to be, at the same time, moved to inoperative position and to be later moved to operative position if there is any outgoing mail.

It is still another object of the invention to provide two such signals, one of which is a weighted swinging signal preferably disposed at one end of the box and the other of which is of different characteristics and is mounted for swinging movement at the side of the box, both signals being operable from substantially one point.

These and other objects of the invention will be fully set forth in the following description made in connection with the accompanying drawings in which like reference characters refer to the same parts throughout the different views, and in which,

Fig. 1 is a view in side elevation of the box with the signals thereon, one of the sig-

nals being shown in inoperative position in dotted lines;

Fig. 2 is a view in end elevation, as seen from the right of Fig. 1, also showing one of the signals in dotted line position;

Fig. 3 is a horizontal section taken on the line 3—3 of Fig. 2;

Fig. 4 is a horizontal section taken on the line 4—4 of Fig. 1;

Fig. 5 is a vertical section taken on the line 5—5 of Fig. 1;

Fig. 6 is a vertical section taken on the line 6—6 of Fig. 1;

Fig. 7 is a vertical section taken on the line 7—7 of Fig. 1; and

Fig. 8 is a vertical section taken on the line 8—8 of Fig. 2, all of said sections being taken as indicated by the arrows.

Referring to the drawings, a mail box 1 is shown which is of common construction, being semi-cylindrical at its top and having vertical sides and ends and being of elongated construction. Said box is illustrated as having a hinged door 2 at one end adapted to be held in closed position by a spring latch 3. In accordance with the present invention, a lever 4 is pivoted at the end of the box opposite the door 2, said lever being pivoted on a threaded member or bolt 5 equipped with suitable nuts for holding the same in the end of the box and for holding the lever in position thereon. The lever 4 has a weight 6 at one end and at its other end carries a signal which, in the embodiment of the invention illustrated, is in the form of a flag 7. This flag conveniently can be formed of a thin piece of sheet metal or other material bent at one end around the rounded end of the lever 4 and connected thereto by headed and nutted bolts 8. The flag can thus be clamped to the lever 4 with sufficient pressure to allow the same to be rotated on said lever and held in any position to which it may be turned.

It will be noted that the end of the lever 4 carrying the flag 7 projects beyond the sides of the box 1. Secured in the side of the box 1 are several brackets 9, 10 and 11, respectively, said brackets being arranged in horizontal alinement. Each of the brackets 9, 10 and 11 is provided with a threaded shank passing through an aperture in the side of the box 1 and clamped thereto by thin nuts engaging said shank. The bracket 9 has two horizontally spaced eyelets 12 formed therein, through the inner one of

which passes a rod 13 which extends along the entire side of the box 1 and projects at the end of the same opposite the lever 4 where it is provided with an operating knob 5 or other suitable handle 14. The rod 13 passes through an eyelet 15 formed in the bracket 10 and through an eyelet formed at the end of bracket 11, and at its end portion is formed with a reversely bent terminal 16, 10 as shown in Fig. 8. The terminal portion 16 is disposed upwardly and when the rod 13 is in its forward position, is adapted to overlie the portion of lever 4 projecting beyond the side of the box, as shown in Figs. 2 and 15 3. The intermediate bracket 10 is formed with a threaded shank at its outer end equipped with nuts between which is pivoted a lever 17 rounded at its upper end and carrying a signal in the form of a flag 18, 20 which flag is similar in structure to the flag 7, and clamped to the outer end of the lever 17 by small headed and nutted bolts which can be tightened as desired. The lever 17 has a laterally projecting lug adjacent its 25 pivot on bracket 10 to which is pivotally connected the end of a rod 19, which rod passes through the outer eyelet 12 in the bracket 9 and projects beyond the end of box 1 where it is provided with a knob or other 30 suitable operating handle 20.

Assuming that the person served has some outgoing mail, the same will be placed in the box 1 and the lever 17 swung to the position shown in Fig. 1 to indicate to the mail 35 carrier that such mail is in the box to be collected. Said person will, at the same, draw forward the rod 13 so that its hooked end will engage over the lever 4 and hold the signal 7 in the position shown in Figs. 1 and 40 2. When the mail carrier approaches the box he will observe the signal 18 in operative position and will know that there is some outgoing mail to be collected. He will therefore stop to remove said mail and will push 45 or strike the knob 20 to depress the lever 17 and flag 18 to the position shown in dotted lines in Fig. 1. This signal will, therefore, stay in this position until again moved to operative position by the person served so 50 that the mail carrier will not make an unnecessary stop to look for mail. At the time the carrier collects the mail, if he has any mail to place in the box he will deposit the same and, in this case, also push or strike 55 the knob 14. This will move the rod 13 longitudinally and move the terminal 16 thereof out of alinement with the lever 4. The weight 6 will then swing the signal 7 to upright position, as shown in dotted lines in 60 Fig. 2. This signal will be observed by the person served from his dwelling and he will know that there is mail in the box for him. When he goes to the box to remove such mail, he may or may not reset the signal 7. 65 If he neglects to set the signal to place the

same in operative position, it will cause no inconvenience to the mail carrier as he will not stop to collect mail unless the signal 18 is in operative position. The trouble with the mail boxes having signals or flags thereon 70 has been that the farmer would not depress the signals to inoperative position after removing the mail from the box. The mail carrier would then see the signal on the next trip and be led to believe that there was outgoing mail in the box and would thus often make an unnecessary stop when there was no such mail. This has resulted in the Post Office Department issuing an order 75 that the carriers need not operate the signal to show that the mail was placed in the box. The carriers, however, may move the signal to inoperative position which the owner has moved to operative position to show that there was dispatch mail in the 80 box. With the two signals, however, arranged as described, no unnecessary stops will be made by the mail carrier and he can operate either signal practically in an instant and with practically no trouble. The 85 signal 7 preferably is constructed to be rotatable so that it can be turned to be best observed from the dwelling of the person served.

From the above description it is seen that 90 applicant has provided a simple and efficient structure of signals having high utility on a mail box. The structure is quite simple and can easily and inexpensively be made and easily and quickly installed on a standard box. When once installed, the device is very easily operated and will give no trouble for maintenance or repair.

It will, of course, be understood that various changes may be made in the form, details, arrangement and proportions of the parts without departing from the scope of applicant's invention, which, generally stated, consists in a device capable of carrying out the objects above stated such as shown and described and set forth in the appended claims.

What is claimed is:

1. The combination with a rural mail box, 115 of a lever pivoted at one end thereof, a flag signal carried at one end of said lever, a weight at the other end of said lever to hold said flag normally elevated, spaced guides along one side of said box, a rod slidable in said guides having an open loop in one end adapted to engage said lever and hold the same in position with the signal depressed, said rod being movable longitudinally to release said lever and having operating means at its end opposite said lever, a second lever pivoted at the side of the box and carrying a signal at one end, a rod disposed at the side of the box pivotally connected to said lever, guiding means through which 120 said rod passes, and operating means at the 125 130

end of said rod disposed adjacent the operating means on said first mentioned rod whereby both signals may be operated simultaneously.

5 2. The combination with a mail box, of a signal on one end thereof in the form of a weighted lever pivoted to said box adapted to normally be moved into signalling position to indicate delivered mail, a second 10 signal pivoted to one side of said box adapted to indicate outgoing mail, elongated control members for said signals dis-

posed in close relation along one side of said box and having their outer extremities disposed in close relation to one another and 15 capable of being simultaneously operated to move said outgoing mail signal into inoperative position and move said delivered mail signal into operative position.

3. The structure set forth in claim 2, and 20 common guide means for said control members.

In testimony whereof I affix my signature.
CHARLES E. BERG.
